UNITED STATES PATENT OFFICE.

LAURITS H. OSTERUD, OF SEATTLE, WASHINGTON.

FOLDING BED.

Application filed July 20, 1921. Serial No. 486,123.

To all whom it may concern:

Be it known that I, LAURITS H. OSTERUD, a citizen of the United States of America, and resident of the city of Seattle, in the county of King and State of Washington, have invented certain new and useful Improvements in Folding Beds, of which the following is a specification.

My invention relates to folding beds and 10 the means for storing them when not in use whereby they may be kept out of sight and also whereby desirable wall space used therein may be minimized.

The type of folding bed and the manner of 15 operating it in opening and closing and in safeguarding against opening and closing except at the time and in the manner intended, resembles in a general way that shown in my Patent No. 1,366,482, issued January 25, 1921.

20 One object of my present invention is to provide an improved bed with a storing or receiving frame or casing so that the bed may be detached therefrom when in use and means whereby the bed-receiving or storing frame may, with or without the bed therein, be put out of sight in the storing cabinet or closet; also to do this in such manner that the bed may be inserted into and removed from the storing cabinet or closet by an edge- 25 wise movement, thereby necessitating only a narrow opening and a shallow storing closet just large enough to contain the bed, making it possible to thereby reduce the wall space occupied by such closet and the closet 30 opening to narrow limits, making it possible to use in other ways more of the wall space than is possible with beds which are otherwise mounted and handled.

Another object of my invention is to provide 35 a method of mounting and handling such beds that the storing cabinet or closet may be constructed in the partition between two rooms and the opening through which the bed is inserted in and removed from said 40 closet may be in the jamb of the door opening which connects said rooms, thus leaving the walls proper of the room undisturbed by the closet and its door.

Another object of my invention is to make 45 the mounting of such a bed one by which the bed may be opened and used in either of the two rooms connected by the door opening; and further, to make the bed used separable from the storage mount and movable 50 independently at will.

Another object is to provide improved

forms of construction for the bed itself as of the means whereby the bed is provided with safety features preventing folding except when the bed is secured to the storing frame, 60 as well as in other respects.

The novel features and constructions of my invention will be hereinafter set forth and then defined by the claims.

The accompanying drawings are intended 65 to illustrate the principles of my invention in the form of construction which is now preferred by me.

Figure 1 shows an elevation of one side of the head end of the bed with parts broken 70 away and in section.

Figure 2 is a horizontal section through one of the head posts at the level of the bed frame pivot and through the head frame just above this. 75

Figure 3 shows a side view of the means employed for securing the top of the head frame to the bed-carrying and storing frame.

Figure 4 shows in perspective half the width of the upper part of the head frame 80 and the manner of securing it to the bed-carrying and storing frame.

Figure 5 is a side elevation of a bed with the bed-carrying or storing frame in section, the bed being shown down by full lines and 85 up by dotted lines.

Figure 6 is a back elevation and Figure 7 a horizontal section, showing the bed-carrying or storing frame and the closet in which it is stored. 90

Figure 8 is a house plan showing certain typical locations and plans for installing my novel bed and mount therefor.

Figure 9 is a side view of a bed in folded position in the bed carrying and storing 95 frame, said frame and part of the wall being shown in section.

Figure 10 is a side view with head post in section, of a means which I prefer to employ to lock the bed to the carrying frame when 100 the bed is folded.

Figure 11 is a top view or plan, in section of the parts shown in Figure 10.

Figure 12 is a view from the front of the locking mechanism shown in Figures 10 and 105 11.

Figure 13 is an end view of the lever by which said locking mechanism is controlled.

The present invention is an improvement in beds of the general type of that shown in 110 the United States Patent No. 1,366,482, issued to me January 25, 1921. This inven-

tion comprises improvements upon the mechanical structures shown in said patent as well as upon the means for mounting and caring for the bed when folded. The broad 5 features of construction and the principles employed therein, are many of them the same as are disclosed in my said patent: I shall not, therefore, herein describe in detail the features which are common in the two cases.

10 The present bed, as in that of the said patent, employs a frame at the head end, that is at the end upon which the bed frame folds, which has head posts 1 connected at or towards their lower end by a cross bar, as 15 10, and connected at their upper end as by a cross bar 11 which functions as a continuous or permanent connection, or by a rod or frame, as the swinging head frame shown in Figures 11 and 12 of which the bar 20 is 20 the top horizontal member and the bars 2 are the vertical side posts.

In the type of construction shown in Figures 9 to 13 inclusive, the head frame 2, 20, connects the upper ends of the head posts 25 when the bed is disconnected from the storage frame or panel and the arms 3 connect the upper ends of the head posts with the storage or holding panel 4 when the bed is folded and stored away, thus connecting the 30 two head posts through the medium of the arms 3 and panel 4.

The bed frame proper, consisting of the side bars 5, with a cross bar 50 at the head end and an analogous cross bar 51 at the 35 foot end, is or may be, to this extent, of any suitable construction. This frame is designed to be or to carry the spring frame. Wherein this frame departs from well known features of construction will be hereinafter described.

40 The bed frame is supported from the head posts 1 by suspension links 52 in manner analogous to that employed in my patent previously referred to. It is also provided with some convenient and suitable type of folding legs, as 53, at the foot end. The use of the terms "head" and "foot" as applied to opposite ends of the bed, is merely a matter of convenience in distinguishing between 45 the two ends. The bedding may be applied in any way desired.

The guiding connection of the head end of the bed frame with the head posts is analogous in principles of mechanics to that 55 shown in my said patent, although differing in construction of parts employed. A lower section of the head piece, containing the vertical posts 22, and connecting bars 23 and 24 is employed, this being fixed to the bed 60 frame. A pivot rod 25 is journaled in posts 22 and has at each end a torsion spring 27 secured to a block 28, fixed relative to the bed frame and a block 29 fixed to the pivot rod 25. The ends of this rod 25 enter slots 65 18 in the inner side face of the head posts 1,

along which it moves as the bed swings between its open and closed positions.

Within each head post is an arm 54 which preferably carries guide wheels or rollers 55 and 56, the whole being freely movable up 70 and down lengthwise of the head post. Each end of the pivot rod 25 is fixed to its respective arm 54, as by having a flattened tip 26 which enters a complementary slot or hole in the arm. The function of the above parts 75 is to counterbalance the bed for easy swinging when opening and closing. This type of construction provides a positive guide between the head end of the bed frame and the head posts. It also encloses the counter- 80 balancing mechanism so that there can be no entanglement of the bedding therewith and adds greatly to the neatness and symmetry of the construction as well as avoiding disarrangements to which exposed moving parts are subject.

In the type of construction shown in Figures 1, 3, 4, and 5, the head frame of the bed has a section, composed of the top rail 11 and the side bars 17, which is pivoted to the main swinging head section 2, 20. The storage or holding panel 4 carries two curved arms 12 which are engaged by the top rail 11 to thereby hold the bed to the storage 90 panel 4.

95 A bar 13 is hinged upon the top rail 11 and has a hook 16 on its outer end adapted to fit over the top cross bar 20, about which the rail 11 swings. The pivoted end of bar 13 has an opening 14 (see Figure 3), which when the arm is dropped to the dotted line position shown in Figure 3, swings over a curved hook 15 carried by the panel 4 and then prevents the rail 11 from being raised, thus preventing removal of the bed from 100 the panel.

105 The arms 17 are pivoted to the upper ends of the head posts 1 by ears 17^a and at the inner side these ears are provided with a U-shaped flange positioned with the axis 110 of its opening approximately aligned with the plane of the arms 17, the opening facing towards the pivot end. As shown the axis of this opening is slightly inclined to the plane of the arms 17.

115 The top bar 20 of the swinging head section has extension ends 20^a adapted to enter said opening when the arms 17 are in the position shown in Figures 3 and 5, this being the position assumed when the bed frame is 120 down or the bed opened. In this position the head section 2-20 may be swung up or down, if the hook arm 13 is raised.

125 With the securing hook arm 13 in this position the retaining hook 15 will not prevent swinging upward of the bar 11, which is necessary to detach the bed from the storing panel 4. Unless the head section 2-20 is up, gravity will cause the arm 13 to fall into the position shown by dotted lines in 130

Figure 3, wherein the head rail 11 is held against swinging up. It is therefore highly improbable that the head rail will ever be raised unless the swinging head section 2-20 is raised into the position shown in Figure 3. When the arms 17 and rail 11 are swung up so as to aline with the head posts, the opening between the wings of flange 17^b faces downward and bar 20 cannot swing down.

The locking of the rail 11 to the retaining arms 12, is secured by the same construction shown in Figures 9 to 11 of my Patent No. 1,366,482, issued to me January 25, 1921. The arm 17 herein shown is the equivalent of the arm 7 of said patent.

When the bed frame swings up, the pivot rod 25, or other suitable part carried by the head end of the bed frame, engages a seat 41 upon a bracket or arm 42 carried by the panel 4, before the bed reaches the upward limit of its swing. In consequence of the laterally offset position of the bar 25, relative to the plane of the bed side-bars 5, the straightening of the lines representing the link 52 and that part of the frame 1 extending from the pivot connection of link 52 therewith to the head end, will further separate the said head end and the point of pivotal connection of said link with the head post.

As the head end of the bed frame cannot sink further, the head posts are thus raised so as to lift them clear of the floor; thus supporting the bed solely from the panel 4. In doing this the angular position of the arms 17 is changed, as is indicated in dotted lines in Figure 5. It is impossible to secure or release the swinging head section 2-20 except when the bed is swung down when it is also attached to the storage and carrying panel 4. Further, as before explained, swinging up of the head rail 11 can only occur when the arm 13 is raised to clear it from the hook 15 and as gravity will hold this arm 13 down when the head frame 2-20 is not raised and with its ends seated in sockets 17^b, it naturally follows that said head section 2-20 would have to be swung up or the bar 11 is locked over the bars 12. Swinging up of the bed can only occur when the head section 2-20 is swung down as this section, if up, would by such action, be drawn down and this is then impossible as it is held by engagement with the flanges 17^b. In this way it is made improbable, if not impossible, to manipulate these parts in any way except in the intended and safe manner and sequence.

The construction shown in Figures 9 to 13 inclusive is a further simplification of construction for securing or retaining the same safely in use and guards against operation in such manner as will cause trouble.

In this construction the swinging head

rail 11 is eliminated and the upper ends of the head posts are not permanently and continuously connected, but are, when the bed is down and in use, connected through the swinging head section 2-20, and when the bed is raised are connected through the securing arms 3.

In this type of construction the head posts are each provided at its upper end with two separated ears or flanges 6 and 60. These provide between them a slot, the plane of which extends from front to rear of the bed, and is so positioned as to receive the flat, yoke shaped end 30, 31 of the arms 3 which are pivotally supported from the carrying panel 4.

The outer ends of the retaining arms 3 each consists of two fingers or yoke arms 30 and 31 which outline a chamber 33 at their inner ends opening between the outer ends of arms 30 and 31 by a narrowed passage 32. The chamber 33 has its outer wall providing shoulders 34 which are perpendicular to the length of the passage 32 and to the length of the arm 3. The lower yoke arm 31 has an inclined lower outer surface 36 which is adapted to engage with the part 61 of the terminal of the head post, so that as they meet when putting the bed into folding and storing position the arm may be slightly raised, if this be necessary. The level of the arm 3 when free may be adjusted by means of a set bolt 39 which screws through an arm or lug 38 and contacts with the base of the pivot ears 37.

Extending lengthwise of and within the head rail 20 of the swinging head section, is a rod 87, to each projecting end of which is secured an arm 8 which is so designed as to interlock with a complementary head 7 which is journaled in the terminal 6 of the head post, which head 7 is also adapted to interlock with the fingers 30, 31 of the retaining arm 3.

Each head 7, which is shown separately in Figure 13, is journaled in the ears 6, 60, of the head post terminal, the sections 73 and 75 being circular. A nut 77 screwing upon the threaded end 76 of stem 75, holds it in place. The section 74 which extends between the ears 6 and 60 of the head post terminal, is of a flattened cross section, as is shown in Figures 10 and 13, and when in proper position will pass freely through the passage 32 between the yoke fingers 30, 31 and cannot be removed therefrom when turned in the other position as shown in Figure 10.

That end of the head 7 which is at the inner side of the head post, has a T-shaped or dovetailed slot 72 formed by the flanges 71. The opposed walls of this slot may be inclined in one or both directions, as is indicated by the dotted line in Figure 11 and by Figure 13, so that when the complementary

flanged or dovetailed edge 82 of lever 8 enters therein it will fit closely.

It is evident that when these interlocking and complementary dovetailed members are engaged they cannot be separated by any movement in the plane of the head frame 2 in a direction transversely of the bed. The head frame is thus interlockingly engaged at its upper edge to strongly support the upper ends of the bed posts and to prevent their movement relative to the head frame 2-20. The bed is thus made much more rigid when detached from its storage panel.

The fit of the flat section 74 of the head 7 within the slot or passage 32 is sufficiently snug, which together with the width of the section 74 and the length of the slot 32, will prevent passage of the section 74 if the angular position of the arm 3 is materially changed. During the time when the bed is secured to the carrying panel 4 the heads 7 are in the position indicated in Figures 10 and 11, in which the flat sections 74 are vertical and the axes of the slots 72 are horizontal. In this position separation of the bed from the carrying panel is impossible.

When the bed is lowered the hook 81 on the extension 80 of arm 8, is released from the pin 87 carried by the bed frame, and the swinging frame 2 raised, the arm 8 being held perpendicular to the plane of the section 2. This places the flanged end of arm 8 in position such that when the frame 2 is swung to the vertical, said arm will enter the slot 72 in head 7. If then the arm 8 be swung down, the head 7 will be turned so as to place the flat section 74 in horizontal position, such that it may readily be removed from the slot 32 and the bed removed from the carrying panel 4.

The arm 8 when swung down causes the spring pressed locking pin 83 to enter a hole in the side bar 2 of the swinging section and hold it securely alongside of said bar. This hole in side bar 2 passes entirely through it and from its inner side receives a hollow plug or thimble 84. A releasing key is used having a terminal section 85 capable of entering the thimble a distance 50 which permits pushing the pin out of the hole in the bar 2. The key is shown as provided with a stop 86, although a plain straight rod of proper diameter will answer.

55 So long as the bed is down the locking head 7 is positioned with its locking section 74 horizontal, that is in position to be entered in the slot in the end of securing arm 3. To close or fold the bed it is wheeled into position to insert the locking or key sections 74 within the slots 32 of arms 3. The arm 8 is then released by use of key 85 and swung up to the horizontal. This key preferably is secured to the storage panel 65 by a chain of a length too short to permit

use of the key except when the bed is in storing position. This permits removal of the arm 8 from the slots 72 and head section 2, 20 to swing down. Hook 81 is engaged with pin 87 to hold section 2, 20 upon the bedding. The bed frame may then be swung up, in doing which the head posts are raised, as has hereinbefore been described, so as to clear their lower ends from the floor. The flat sections 74 are then in vertical position and no means are provided for turning them to release position except by connecting the rod 8 thereto, which can only be done after lowering the bed and locking its parts so that it cannot be folded. Means are thus provided, largely automatic in action through steps which are compulsory, whereby the bed cannot be removed from its storage carrier unless it is first lowered and its parts locked together so that it cannot fall down or be folded and also so that it can only be folded after it has been locked upon its carrier.

The bed described is capable of being used independently of a storage closet or cabinet, but is intended for convenient storage within a closet where it will be out of sight. While the closet may open for the reception of the bed upon its broad face, I prefer to use a construction wherein the closet opening is at one minor side, the bed entering edgewise therein. Such a construction is shown in Figures 5, 6, and 7, and in Figure 8 is shown a typical floor plan of a house showing characteristic locations for such bed receiving closets. The characteristic feature about my plan of storing the bed when not in use is the removable supporting of the bed upon or in a carrying frame so as to be clear of the floor and the bodily movement of said carrying frame with its contained bed into and from the storage closet.

The bed receiving and storage frame 40 resembles a frame or shallow box having one major face open for the reception of the bed. It may or may not have in the other major face, an opening in which is the panel 4 upon which the bed is supported when stored. This panel may be fixed in the frame or, as shown in the drawings, be carried by pivots 43 at top and bottom so as to be turnable to thereby face oppositely, making it possible to remove the bed into either of two rooms, if as has been indicated in Figures 5, 6, and 7 the storage closet is located in the partition between two rooms, the communicating opening being big enough to accommodate the width of the bed.

The manner of supporting the bed storing frame for easy movement into and out of the storage closet may be varied. The manner indicated is to provide it with carrying wheels or trolleys 45 which run upon over-

head tracks 46. Ventilating openings 59 may be provided for the storage closet.

One of the side walls 47 of the storing frame may be made to serve as the closure 5 of the closet or separate doors, as is indicated at 48 in Figure 8, may be used. Also, the panel 4 may be located in the center of the frame 40 and a bed secured to each side thereof, as has been indicated at 49 in 10 Figure 8. In such case two beds are stored in the same closet. The closets may have openings at each minor side so that, as in closets 9 in Figure 8, the bed may be used either in the house or upon a porch.

15 By the above plan the beds when not in use are stored in closets which need be only just large enough to hold the bed, there being no requirement for extra room which is needed only for getting the bed in or out of 20 the closet. A smaller closet will amply suffice for holding this bed than is required when the bed is swung into a closet and then turned into storing position. It also makes possible a substantially complete 25 utilization of the wall space of a room for placing furniture, hanging pictures or otherwise.

What I claim as my invention is:

1. A folding bed comprising head posts, a 30 bed frame, means for connecting said bed frame with the head posts to permit vertical movement of the bed frame upon the head posts in swinging between open and closed positions, a head section pivoted upon the bed frame and means for lockingly engaging said head section with the upper ends of the head posts to form a binding connection between the head posts.

2. A folding bed comprising head posts 40 which are disconnected at their upper end when the bed is folded, a bed frame adapted to swing between horizontal and vertical positions, a head frame pivoted upon the bed frame and means for securing the upper 45 parts of said head frame and the head posts together to supportingly engage and prevent separation of the head posts when the bed is opened.

3. A folding bed comprising head posts 50 which are disconnected at their upper end when the bed is folded, a bed frame adapted to swing between horizontal and vertical positions, a head frame pivoted upon the bed frame to swing towards and from the bed posts, and means for interlockingly engaging the upper parts of said head frame and the head posts to bind them together against separation when the bed is opened, and means for disengageably securing the upper ends of said head posts to an independent support and by the same act releasing the connection between the said head frame and head posts, so that the bed may be folded.

4. A folding bed comprising head posts

having rigid permanent connection between their lower ends only, a bed frame having a vertically movable pivot connection with said head posts, suspension links pivoted to the head posts and to the bed-frame inwardly from its head end, a head frame pivoted upon the bed frame to swing towards and from the head posts, and means whereby when the bed is lowered the upper part of said head frame may be lockingly secured to the upper part of the head posts to resist relative movement between said frame and the head posts.

5. A folding bed comprising head posts, a cross bar connecting their lower ends, a bed frame having a vertically movable connection with said head posts, and supported to permit swinging between horizontal and vertical positions, a head frame pivoted to said bed frame, and means operable when the bed is lowered to secure the said head frame to the head posts to form a transverse supporting connection between the head posts.

6. In a folding bed, in combination, a bed storing frame, a bed having head posts, a bed frame pivotally carried from said head posts and a head section pivoting upon the bed frame, a lock for securing the head posts to the storing frame, a lock for securing said head section to the head posts, said locks each having a common member movably mounted upon the head posts and adapted to be disengaged from its complementary member of one lock when engaged with its complementary member of the other lock.

7. In a folding bed, in combination, a bed storing frame, a bed having head posts, a bed frame pivotally carried from said head posts and a head section pivoting upon the bed frame, a lock for securing the head posts to the storing frame, a lock for securing said head section to the head posts, and a member common to each of said locks, adapted to maintain their parts in respectively opposite relation as to holding and releasing of their interlocking parts.

8. In a folding bed, a storing frame, a bed frame, head posts from which the bed frame is pivotally supported, retaining arms pivoted upon the storing frame, said retaining arms and the head posts having complementary parts engageable when the bed is opened, and means for locking said complementary parts actuated by the folding of the bed.

9. In a folding bed, head posts each having a rearwardly opening socket in its upper end with its axis extending lengthwise of the bed, locking members rotatively mounted in said posts and having a flattened section extending across said socket opening, retaining arms pivoted to a bed-storing support to have a vertical movement

of their free ends, said free ends being forked and adapted to enter the socket and to pass over the flattened sections of said locking members when the latter are presented truly edgewise thereto, and means actuated by the folding of the bed to change the relative angular position of said retaining bars and locking members and to thereby prevent their separation.

10 10. In a folding bed, head posts, a bed frame pivotally carried from the head posts to swing between horizontal and vertical positions, a head section pivotally carried by the bed frame, a rod journaled in the said head section, complementary locking members carried by said rod and the head posts, a control lever secured to said rod and means for locking said control lever in position to maintain the said head frame and post-locking members in locked position.

11. In a folding bed, head posts, a bed frame pivoted from the head posts to swing between open and closed positions, a head frame pivoted to the bed frame to be drawn downwardly when the bed is swung toward closed position, interlocking members carried by the head post and by said head frame interlockingly engaging when the head frame is raised to prevent swinging of the bed frame, a second set of interlocking members carried by the head post and by the upper part of the swinging head frame and containing a rotative socket member and an entering projection, means for turning said socket member into position to receive and discharge said projection by the swinging of the head frame and into a position at an angle with the aforesaid position sufficient to prevent release thereof by swinging of the head frame, and means for locking said socket member in the latter position.

12. The combination in a folding bed of head posts, a bed frame swinging upon said head posts between open and closed positions, a head frame swinging upon the bed frame, retaining members adapted to hold the bed in its storage position and having a yoke provided with a restricted entrance gap, a locking member rotatively mounted upon the head posts and having a flattened section adapted to edgewise enter said entrance gap of the retaining yoke, said locking member and the swinging head frame having one a socket and the other a complementary entering member, the two interlocking parts of said locking member being positioned so that when one is in release position the other is in holding or locked position and an operating arm secured to the complementary member of the locking device carried by the head frame.

13. The combination with a folding bed having head posts, a bed frame swinging thereon to fold and open, retaining arms pivotally mounted on a storing member to

swing vertically, means for locking the bed against folding when open, means for locking the folded bed to said retaining bars, a locking member of each of said means being connected together to place them in inverse relation to their complementary locking members, whereby when one of said means are in locked position the other is in unlocked position.

14. The combination with a folding bed having head posts, a bed frame swinging thereon, retaining arms carried at the point of storage of the folded bed, means for locking the bed against folding where opened, means for locking the bed to the outer ends of said retaining arms, a manually operated controlling member for operating both of said locks and connecting therewith to place the parts of one in locking position when the other is freed, and means operated by the folding of the bed to place the parts of the second named lock in non-releasable position and to place them in releasable position when the bed is opened.

15. In a folding bed, in combination, head posts, a bed frame swingingly supported from said head posts, bed retaining arms pivoted by one end to the member which carries the bed when it is stored, complementary means carried by the bed posts and manually operated to place said parts into position to lock the posts to the retaining arms, and means operated by the swinging of the bed into folded position to complete the locking action and to put the same parts into releasable position when the bed is lowered.

16. A folding bed comprising head posts, a bed frame swinging upon the head posts between open and closed positions, retaining members for holding the bed in its storage position, means carried by the head posts adapted to be placed in engagement with and to be disengaged from said retaining members by bodily movement of the bed over the floor, a head frame pivoted upon the bed frame to swing down upon the bedding, locking means carried by said head frame and the head posts and engaging when the head frame is raised to thereby prevent folding of the bed, said locking means comprising members carried by the head posts and complementary members carried respectively by the said retaining members and by the head frame and means carried by the said head frame and operating both of said last named locking means.

17. The combination with a folding bed of means for retaining the bed in stored position comprising arms pivoted at the point of storage and having outer yoke ends with restricted openings, locking members of flattened cross section carried by the bed and adapted to edgewise enter said yoke

openings, and means for shifting the axial position of said locking member relative to the axis of the yoke openings to thereby prevent separation of the two.

18. The combination with a folding bed of means for retaining the bed in stored position comprising arms pivoted at the point of storage and having outer yoke ends with restricted openings, locking members of flattened cross section carried by the bed and adapted to edgewise enter said yoke openings, a lock adapted to engage folding parts of the bed structure and adapted in one position to prevent folding of the bed, one part of said bed lock and the flat sectioned part of the lock for holding the bed in storing position being connected to be operated together and oppositely as to releasing and freeing the parts connected thereby.

19. In a folding bed, head posts connected at their lower ends, a bed frame having a vertically slideable connection with the head posts, supporting links pivoted on the head posts and the bed frame outwardly from the head posts, a head frame pivoted to the bed frame, said head frame and the head posts having parts interlocking when the

head frame is swung up to prevent swinging of the bed frame, locking members rotative in the head posts, complementary locking members carried by the head frame, said complementary locking members having dovetailing parts forming a tying connection between the upper ends of the bed posts, and means for turning said locking members to a position to permit free engagement and separation thereof by swinging the said head frame and to another position which prevents swinging of said head frame.

20. A folding bed comprising a fixed storing member, head posts, a bed frame pivoted to swing upon the head posts, a head frame pivoted to swing upon the bed frame, means for locking the head frame to the head posts when the head frame is raised, means for locking the head posts to the storing member when the bed is folded, said two locking devices being connected to oppositely function, whereby each is released when the other is engaged and vice-versa.

Signed at Seattle, King County, Washington, this 2nd day of July 1921.

LAURITS H. OSTERUD.
